UNITED STATES PATENT OFFICE.

WELLINGTON M. BROWN, OF LAPORTE, MICHIGAN, ASSIGNOR OF ONE-HALF TO SHELDON RINEHART, OF LAPORTE, MICHIGAN.

TRACTION-ENGINE.

SPECIFICATION forming part of Letters Patent No. 762,380, dated June 14, 1904.

Application filed March 31, 1904. Serial No. 200,939. (No model.)

To all whom it may concern:

Be it known that I, WELLINGTON M. BROWN, a citizen of the United States, residing at La-
porte, in the county of Midland and State of
Michigan, have invented certain new and use-
ful Improvements in Threshing-Engines; and
I do hereby declare the following to be a full,
clear, and exact description of the invention,
such as will enable others skilled in the art to
10 which it appertains to make and use the same.
This invention is an improved front-axle
construction for traction or plain threshing
engines which provides for lateral adjustment
of the front end of the boiler.
15 As is well known it is customary to belt
the belt-wheel of a traction-engine standing
at a distance from the threshing-machine to
a driving-pulley on the machine to be driven,
usually located inside a barn. To insure safety
20 from fire, the engine is usually required to be
not less than fifty feet from the barn. It is
thus seen that a long belt is necessary. It is
found in practice that these long belts are
thrown out of line very easily. A strong
25 wind frequently shifts the belt, or the pulsation
of the engine causes the engine-wheels to shift,
throwing the belt off the pulley and partly
displacing it, thereby greatly reducing
the power-transmitting capacity of the belt.
30 It is then necessary to move the engine back
into line, and this has heretofore been accom-
plished by jacking the front wheels to one
side or the other. To more easily attain this
object, I have devised a simple hand-operated
35 means for shifting the king-bolt, which is at-
tached to the front end of the boiler, along
the front axle without moving the engine-
wheels.

The construction and operation of my de-
40 vice will be more readily understood by ref-
erence to the accompanying drawings, in
which—

Figure 1 is a front elevation of an engine
with my improvement attached. Fig. 2 is a
45 front view, and Fig. 3 is a top view, of the
device. Fig. 4 is a vertical section on the
line $\alpha\alpha$ of Fig. 2.

In the top of a block 1, mounted to slide in

grooved guides 2, fastened to the front axle
3, is provided a footstep-bearing 4 for the 50
king-bolt 5. Near the ends of the axle are
threaded lugs 3^a and 3^b, in which work set-
screws 6 and 7, that bear against opposite ends
1^a and 1^b of the block 1 to move it along the
axle. A set-screw 8 is provided in the front 55
of the guide 2 to lock the block 1 firmly in
any location.

The operation will be easily understood by
reference to Fig. 1, which shows in full lines
the front end of the engine and boiler in a 60
position from which it is desired to shift it,
say, to the right, for the purpose above noted.

First the set-screw 8 is unscrewed, then the
screw 7 on the right is unscrewed and the
screw 6 on the left is screwed up, moving the 65
sliding block 1 to the right and shifting the
boiler (and the belt-wheel B) into the position
shown in dotted lines, thus bringing the belt
back into line. The set-screw 8 is again
screwed in to lock the block 1 firmly in this 70
new position. Similarly, the boiler and belt-
wheel may be shifted to the left, if desired.

By the means above described I have pro-
duced a hand-operated device for laterally ad-
justing the front end of a traction or thresh-
ing engine to keep the belt in line, which is
simple in construction and not difficult to ap-
ply. In its operation it is independent of any
75 working part of the engine and may be used
to shift the boiler along the front axle whether
the engine be running or not.

What I claim as my invention, and desire
to secure by Letters Patent, is as follows:

1. In combination with the front axle and
king-bolt of an engine of the class described,
80 means for shifting the belt-wheel of said en-
gine laterally, said means comprising guides
on said front axle, a sliding block mounted in
said guides and having a footstep-bearing for
said king-bolt, and means independent of the
85 driving mechanism of the engine adapted to
shift said block along the guides for the pur-
pose set forth.

2. In combination with the axle and king-
bolt of an engine of the class described, guides
90 secured lengthwise said axle; a block slidable

along said guides and having a recess to receive said king-bolt; threaded lugs near the ends of the axle; screws threaded in said lugs; the inner ends of said screws bearing against said sliding block; and a set-screw in said guides to lock the block, substantially as described.

In testimony whereof I affix my signature in presence of two witnesses.

WELLINGTON M. BROWN.
